UNITED STATES PATENT OFFICE

127,622

DESIGN FOR A TEXTILE FABRIC

Herman R. Terhune, Ridgewood, N. J., assignor
to American Bleached Goods Company, Inc.,
New York, N. Y., a corporation of Delaware

Application March 3, 1941, Serial No. 99,335

Term of patent 14 years

To all whom it may concern:

Be it known that I, Herman R. Terhune, a citizen of the United States of America and a resident of Ridgewood, county of Bergen, State of New Jersey, have invented a new, original, and ornamental Design for Textile Fabrics, of which the following is a specification, reference being had to the accompanying drawing, forming part thereof.

Figure 1 shows a plan view of a piece of the fabric embodying the design, a single repeat unit of which is contained between the broken lines, which unit is repeated in regular succession, as indicated by the extensions beyond the broken-

line unit boundaries. For clarity in illustration, the showing of the fabric is on an enlarged scale, being approximately one and one-half times the original size.

Figure 2 is a view similar to that of Fig. 1 on a further enlarged scale, being an enlargement approximately to three times the original size.

The subject matter of this application is a continuation-in-part of my co-pending application, Serial No. D-96,821, filed November 26, 1940.

I claim:

The ornamental design for a textile fabric, substantially as shown and described.

HERMAN R. TERHUNE.
